UNITED STATES PATENT OFFICE.

OTTO SCHLATZ AND AUGUST SCHLATZ, OF REPUBLICAN CITY, NEBRASKA.

LATCH.

1,071,802.

Specification of Letters Patent. Patented Sept. 2, 1913.

Application filed February 24, 1913. Serial No. 750,442.

To all whom it may concern:

Be it known that we, Otto SCHLATZ and August SCHLATZ, citizens of the United States, residing at Republican City, in the 5 county of Harlan and State of Nebraska, have invented certain new and useful Improvements in Latches, of which the following is a specification, reference being had to the accompanying drawings.

10 This invention relates to new and useful improvements in latches and more particularly to that class adapted to be used in connection with hinged doors, gates or the like.

An object of this invention is the provision of a latch such as described, which will 15 retain the door or gate either in a closed or open position.

Another object of this invention is the provision of a gate or door latch which can 20 be operated to release the said gate or door from either side, when in its closed position.

A further object of this invention is to improve and simplify devices of this character, rendering them comparatively simple 25 and inexpensive to manufacture, reliable and efficient in use and readily operated.

With the above and other objects in view, this invention resides in the novel features of construction, formations, combinations 30 and arrangements of parts to be herein-after more particularly described, claimed and illustrated in the accompanying drawings, in which—

Figure 1 is a horizontal sectional view 35 taken through a building, showing our improved latch in plan; and Fig. 2 is a transverse sectional view taken through the latch plate, showing the latch in side elevation.

Referring to the accompanying drawings 40 by similar characters of reference throughout the several views, the numeral 10 designates a fragment of a building provided with a door opening 11, to one side of which is hinged, as at 12, the door 13. The vertical free edge of this door 13 is formed 45 with a transversely extending notch 14 adjacent to which is secured upon the outer side of the door a latch plate 15. This said plate 15 is secured in substantially parallel 50 relation to the upper and lower edges of the door and has its forward end positioned flush with the edge of the notch 14 intermediate the ends thereof. The outer end of the latch plate 15 is extended at right 55 angles thereto flush with the bottom of the notch 14 to produce the forwardly tapering

arm 16 to which is pivotally secured adjacent its juncture with the latch plate 15, as at 17, a latch 18. This latch extends a suitable distance beyond the opposite sides of the door 13 and is tapered at its terminals, as clearly illustrated by the numeral 19 throughout the several figures of the drawings. The upper edge of the inner extremity of the latch 18 is notched, as at 20, 60 while a similar notch 21 is provided in the lower edge of the outer extremity thereof. These notches 20 and 21 produce resultant barbs 22 and 23 for a purpose to be later disclosed. 65

The forward terminal of the latch 18 is offset at right angles thereto to produce an operating finger 24 by the means of which the opposite ends of the latch can be raised or lowered as desired. This finger 24 also 70 engages the upper edge of the arm 16 at its forward terminal limiting the downward movement of the latch relative thereto. 75

An aperture 25 is formed in the latch plate 15 adjacent the supporting arm 16 80 and in the same is secured a tension spring 26, the opposite extremity of which is looped as at 27 and passed around the finger 24, while an intermediate loop 28 formed thereon is secured to the arm 16 by a pin 29 or 85 other suitable similar fastening device. This spring 26 serves to yieldingly force the forward extremity of the latch 18 downwardly until limited in such movement by the contact between the finger 24 and arm 16. A 90 catch 30 is secured to the interior of the building in the path of the latch 18 and consists of an attaching plate 31 twisted as at 32 and bent laterally to produce the catch proper 33, in which is formed an engaging 95 opening 34 adapted to receive the inner end of the latch 18 and by its engagement with the barb 22 retain the door 13 in its closed position. When it is desired to release the door, all that is required is to raise the finger 100 24 which lowers the inner end of the latch 18, consequently releasing the barb 22 from the upper edge of the opening 34, which permits the opening of the door. 105

A staple 35 is secured to the building 10 a 110 suitable distance beyond the hinged side of the door. This staple 35 is arranged in the path of the latch 18 and in such position that when the door is forced outwardly to the limit of its movement, this staple 35, by 110 its contact with the lower side of the barb 23, raises the outer end of the latch 18

against the tension of the spring 26 until the arch of the said staple 35 engages the notch 21 behind the shoulder of the barb which obviously retains the door in its open 5 position against any undesired movement. If, however, it is desired to release the door and close it, a slight pressure upon the opposite end of the latch will raise the barb 23 from its engagement with the staple 35 10 and the door can be readily closed.

From the foregoing disclosures, it will be manifest that a latch is provided which will fulfil all of the necessary requirements of such a device, and while the same is illustrated and described as being used in connection with a door, we do not desire to be limited to such use, but intend to use the same in connection with gates or other suitable objects to which the various parts 15 thereof will adapt themselves. It should be further understood in this connection that various minor changes in the specific details of construction can be resorted to within the scope of the appended claims, without departing from or sacrificing any of the 20 advantages of the invention.

Having thus fully described this invention, what we claim as new and desire to protect by Letters Patent is:—

30 1. In a device of the character described, the combination with a latch plate, of an arm formed thereon and extending perpendicularly thereto, a latch pivoted to said arm, said latch extending parallel to the arm 35 and perpendicularly to the plate, a lateral

finger formed upon one end of the latch and arranged to engage the upper edge of the arm, a spring secured to the latch plate, arm and finger for normally forcing the finger into engagement with the arm and retaining 40 the latch in its normal position, the said latch being notched at its opposite ends and opposite edges to form barbs, and catches for engagement with the barbs.

2. In a device of the class described, the 45 combination with a latch plate having a laterally extending arm thereon, disposed perpendicular thereof; of a latch pivoted intermediate of its ends to the laterally extending arm of the latch plate and projecting on 50 both sides of the latter, an angular finger formed on one end of said latch and adapted to rest in engagement with the upper edge of said arm, at the outer end of the latter to limit the movement of said latch in one direction, and spring means in connection with said latch plate and finger to normally retain said latch in a position to dispose the angular finger thereon in engagement with the arm on the latch plate, said latch being 55 notched at its ends to form barbs, whereby a locking means is provided thereon.

In testimony whereof we hereunto affix our signatures in the presence of two witnesses.

OTTO SCHLATZ.
AUGUST SCHLATZ.
